Thomas F. Lamb, Inventor;

UNITED STATES PATENT OFFICE.

THOMAS F. LAMB, OF NEWARK, OHIO, ASSIGNEE TO THE AMERICAN BOTTLE COMPANY, OF NEWARK, OHIO, A CORPORATION OF OHIO.

BOTTLE-HANDLING DEVICE.

1,091,671.

Specification of Letters Patent. Patented Mar. 31, 1914.

Application filed October 10, 1913. Serial No. 431,331.

To all whom it may concern:

Be it known that I, THOMAS F. LAMB, a citizen of the United States, residing at Newark, in the county of Licking and State of Ohio, have invented certain new and useful Improvements in Bottle-Handling Devices, of which the following is a specification.

My invention relates to an apparatus designed for use as an adjunct to a bottle-blown or molding machine, and the main object of the invention is to provide an improved apparatus for receiving freshly made bottles in succession, from the blowing or molding machine and arranging them in convenient order and position to be transferred by the usual workman's paddle to the annealing oven or leir.

The apparatus of my present invention is of the same general character and is designed for the same general purpose as the apparatus disclosed and claimed in my former Letters Patent No. 1,064,746, granted June 17, 1913; the chief improvement of the present apparatus upon the apparatus disclosed in the said patent residing in the substitution of an intermittently rotated circular table receiving the bottles upright thereon for the stationary table and bottle-shifting devices of the said patent.

My invention, its mode of operation, and the advantages secured thereby will all be readily understood when considered in connection with the accompanying drawings which illustrate the preferred embodiment of the invention, and in which—

Figure 1 is a side elevation of the complete machine. Fig. 2 is a top plan view of the same. Fig. 3 is a perspective side elevation, with the bottle-receiving table and its parts broken away and illustrating the operating parts at the opposite extreme of their movement from that shown in Fig. 1. Fig. 4 is a detail view illustrating the mode of pivoting the oscillating bottle-receiving pan.

Referring to the drawings, 5 designates as an entirety the base-plate on which the mechanism is supported, which base-plate is preferably mounted on fore and aft trucks 6 and 7, respectively, for convenient portability and adjustment relatively to the blowing or molding machine which it serves. On the fore part of the truck is secured a vertical stationary spindle 8, on which is rotatably mounted a circular table or platform com-

prising, as here shown, a ring-plate 9, radial spokes 10 supporting the ring-plate at their outer ends, and a central hub 11 journaled on the spindle 8 and itself stepped upon a vertical collar or sleeve 12 surrounding the spindle 8; said collar 12 in turn being stepped upon a stationary collar 13 secured to the base-plate 5. To the forward end of the base-plate 5 are also secured a series of inclined braces or supports 14 carrying at 65 their upper and outer ends a paddle-rest 15. This latter is mounted on the braces 14 with capacity for limited endwise adjustment by means of slots 16 formed through the paddle-rest and clamping bolts 17 mounted in 79 the braces 14 and engaging said slots. On the opposite ends of the paddle-rest 15 are guides 18, in which are slidably mounted bolts 19 carrying a brake-shoe 20 adapted to engage the periphery of the table-ring 9; 75 said bolts and brake-shoe being urged toward the periphery of the table-ring by springs 21 secured at one end to the bolts and at their other ends abutting against the outer ends of the guides 18. The function 80 of the brake-shoe 20 is to prevent overthrow during the intermittent forward turning movement of the bottle-receiving table as well as to prevent backthrow or slip of the table during the return movement of the 85 table-actuating pawl, as hereinafter described.

Journaled upon and transversely of the rear end of the base-plate 5 is a rock shaft 22, on one end of which is a crank-arm 23 (Fig. 90 2) connected by a pitman 24 to a crank-disk 25 fast on a shaft 26; this latter shaft being geared to turn in timed relation to the bottle-blown or molding machine and in a fixed ratio to the rotary movement of the 95 latter. Fast on the opposite end of the rock shaft 22 is a slotted crank-arm 27, to which is adjustably connected by a coupling block 28, a connecting-rod 29, the other end of which is adjustably secured to a slotted radius arm 30 that extends from the collar or sleeve 12. Pivoted upon an 100 upstanding lug 31 on the outer end of the arm 30 is a counter-weighted pawl 32 that engages the under side of the ring-plate 9 and, under the oscillation of the arm 30 is successively brought into driving engagement with a series of depending lugs 33 on the under side of said ring-plate. The upper 105 surface of the ring-plate is preferably formed 110

with an annular series of shallow depressions forming bottle-seats 34, and the lugs 33 correspond in number and in spaced relation to the bottle-seats 34. From the foregoing it will readily be seen that at each complete rotation of the crank-disk 25 the rock shaft 22 makes one complete to-and-fro oscillation, carrying the pawl 32 back into engagement with the next lug 33, and then advancing the rotary movement of the ring-plate to an extent equal to the space between two adjacent lugs.

Referring now to the mechanism for transferring the freshly made bottles from the blowing or molding machine onto the intermittently revolving table, 35 designates a quadrant-shaped pan, to the under side of which is secured a bail-shaped metal strap 36 (Fig. 4) by which it is pivoted, through a horizontal hinge bolt 37, to an upright support 38 on the base-plate 5; the pan itself being slightly inclined in a direction transverse to the base-plate 5, as shown in Fig. 4. As shown in Fig. 2, the pan 35 is notched out through a little more than one-half the length of one of the radial sides thereof, and to the remaining portion of said notched outside is secured an upright stop-block 39 supported by a frame 40 and serving to receive the impact of the open ends of the freshly made bottles as they are delivered on to the pan 35 by a suitably positioned stationary chute 41 (Fig. 3). The other radial side of the pan 35 is provided with a flange 42, and the curved side is also provided with a flange 43, although I have found in practice that this latter may be dispensed with, since the bottle, when the pan is tilted, automatically shifts its axial position through a right-angle without appreciable endlong sliding movement. The pan 35 is normally maintained in elevated or bottle-receiving position by suitable means, such as the tension spring 44 connected at one end to the frame 40 that carries the impact-block 39 and at its opposite end to a fixed post 45 arising from the base-plate 5.

Coöperating with the pan 35 is a device for transferring the bottle from the latter up onto the rotary receiving table, comprising the following parts.

46 designates an auxiliary rock shaft journaled transversely of the base-plate 5 substantially midway between the table spindle 8 and the rock shaft 22. Fast on rock shaft 46 is an arm 47, on the free end of which latter is mounted the cradle 48 that, in the lowered position of the arm 47 shown in Figs. 1 and 2, registers with the notched side of the pan 35, and receives the bottles successively from said pan. More specifically described, the cradle 48 is directly mounted, by its stem 48', upon a horizontally extending arm 49, which latter is extended a slight

distance beyond the connection of the cradle thereto and terminates in an upwardly turned finger 50, for a purpose hereinafter described. Fast on one end of the auxiliary rock shaft 46 is a slotted crank-arm 51 that is connected by a link 52 to a similar crank-arm 53 fast on one end of the main rock shaft 22. To provide an elastic connection between the link 52 and the crank-arm 53 that will avoid shocks and jars, the pivot pin 54 connecting said parts is cushioned on either side by springs 55 and 56 carried in a spring-box or housing 57 on the end of the link 52.

Referring back to the rotary receiving table, 58 designates a radius arm keyed to the spindle 8 and, at its outer end, overlying the inner portion of the ring-plate 9. Pivoted to said outer end of the radius arm 58 is a bottle-centering device in the form of a movable stop-plate 59, preferably concave to substantially fit the contour of the body of the bottle. The stop-plate 59 is normally drawn inwardly by an extension spring 60, a link-rod 61 connecting one end of said spring with an anchor boss 62 keyed to the spindle 8. The stop-plate 59 has an extension 63 on the opposite side of its pivot, forming a contact member that is engaged by the finger 50 as the bottle is advanced over the edge of the table; in the manner hereinafter described.

64 designates an arc-shaped guide or slide-way extending between the base-plate 5 and the upper surface of the ring-plate 9 of the receiving table. The bottle-engaging surface of this guide 64 is convex, as shown, the guide being formed on an arc whose center of curvature is approximately in the axis of the auxiliary rock shaft 46. The lower end of the cradle 48 reciprocates above the outer convex surface of the guide 64 in comparatively close proximity thereto, the bottom of the bottle in the cradle sliding over the guide 64 as it is raised by the cradle and pushed onto the ring-plate 9.

Secured to the base-plate 5 is a short upstanding rod 65 having a horizontally bent end 65' that forms a stop limiting the downward swing of the cradle-carrying arm 47 to a position at which the cradle 48 lies substantially flush at one edge with the tilting pan 35 in the lowered position of the latter.

To check the bottles, when received from the chute 41 onto the pan 35, from rolling down and off the discharge edge of the latter before the cradle 48 has reached bottle-receiving position, I provide a movable guard comprising a rod or bar bent to form a guard-arm 66 (Fig. 2) overlying the pan 35 and an actuating arm 67 therefor, which latter is pivoted at its outer end on the upper end of the standard 45. One arm of the bail 36 to which the pan 35 is attached is extended downwardly some distance below the hinge 130

pivot 37, and to the same is secured a forwardly projecting arm 68 having a rear extension 69 connected to the actuating arm 67 of the guard 66 by a link 70.

3. The operation of the apparatus is as follows: When the parts are in the position shown in Fig. 3, a freshly made bottle is sliding down the chute 41, while the cradle 48 is just delivering the previous bottle onto the rotary table. The bottle slides from the chute 41 onto the pan 35, the mouth of the bottle striking against the impact-block 39. At the same time the arm 47 begins to swing downwardly, and as the horizontal arm 49 carried thereby strikes and depresses the arm 68, the pan is tilted downwardly and forwardly, and simultaneously the guard-arm 66 is raised, thus releasing the bottle previously received on the pan 35 and allowing it to roll down onto the cradle 48, which latter reaches its lowermost position simultaneously with the completion of the forward and downward tilting movement of the pan. Thereupon the arm 47 swings upwardly, advancing the bottle in the cradle 48 over the curved guide 64, and simultaneously permitting the pan 35 to tilt back under the influence of spring 44, and the guard-arm 66 to return to normal position. As the cradle 48 advances the bottle off the end of the guide 64 and onto the ring-plate 9, the end of the finger 50 strikes the contact-member 38 of the centering device, thereby advancing the concave bottle-engaging portion 59 of said device to the proper position to arrest the bottle exactly over one of the bottle-seats 34. While a bottle is thus being delivered over the guide 64 and onto the receiving table, the actuating pawl 32 is advanced into engagement with the next lug 33 of the table, and, on the return or downward swing of the arm 47, the finger 50 releases the centering device, allowing it to be drawn back by the spring 60 out of engagement with the bottle, and simultaneously the table is advanced one step, bringing the next bottle-seat 34 opposite the delivery end of the guide 64. In this way, the bottle-seats 34 are successively filled with bottles, the last being allowed to accumulate on the table until there is a row of bottles opposite the paddle-rest 14. Thereupon the workman, resting his paddle upon the rest 13 and engaging the paddle wire over the upstanding necks of some or all of the bottles lying opposite the paddle-rest, by a deft movement lifts them onto the paddle and conveys them to the leir. By the time he has returned, the apparatus has advanced the table to a position in which another row of bottles is opposite the paddle-rest ready for removal in a similar manner.

The brake or drag 20 checks any excess movement of the rotary table as well as any back movement thereof during the return or

idle movement of the pawl-carrying arm 30. The purpose of the adjustable mounting of the paddle-rest is to provide for a longer or shorter cooling period for the bottles on the rotary table and before removal to the leir, according to the heat at which the bottles emerge from the bottle-forming machine.

From the foregoing it will be seen that the apparatus of my present invention, like that of my former patent, above referred to, makes necessary the services of only a single attendant to effect the transfer of the freshly made bottles from the bottle-making machine to the annealing oven; and it improves upon the apparatus of my former patent aforesaid to the extent that it avoids bodily shifting or moving of the hot bottles relatively to the receiving table or platform after they have been received upon the latter, avoiding danger of breaking or sticking, while arranging them in suitable position to be transferred by the paddle to the annealing oven.

It will be evident to those skilled in the art that the machine as shown and described is capable of variation and modification in minor details without involving any departure from the principle involved or sacrificing any of the advantages thereof. Hence I do not limit the invention to the exact structure and mechanism shown and described.

I claim—

1. In a bottle-handling device, the combination with a table rotatably mounted on a vertical axis, and means for imparting thereto a step-by-step rotary movement, of a paddle-rest located opposite and substantially flush with one side of said table, and means for successively delivering bottles in upright position to the marginal portion of said table.

2. In a bottle-handling device, the combination with a table rotatably mounted on a vertical axis, and means for imparting thereto a step-by-step rotary movement, of a paddle-rest located opposite and substantially flush with one side of said table, a brake engaging the periphery of said table, and means for successively delivering bottles in upright position to the marginal portion of said table.

3. In a bottle-handling device, the combination with a table rotatably mounted on a vertical axis, and means for imparting thereto a step-by-step rotary movement, of a paddle-rest located opposite and substantially flush with one side of said table, a spring-actuated brake mounted on said paddle-rest and engaging the periphery of said table, and means for successively delivering bottles in upright position to the marginal portion of said table.

4. In a bottle-handling device, the combination with a table rotatably mounted on a

- vertical axis and having a circular row of bottle-seats formed in the upper surface thereof, of means for imparting a step-by-step rotary movement to said table, means 5 for successively delivering bottles in upright position onto said bottle-seats, and a movable bottle-centering device coöperating with said bottle-delivering means to position said bottles upon said seats.
- 10 5. In a bottle-handling device, the combination with a table rotatably mounted on a vertical axis and having a circular row of bottle-seats formed in the upper surface thereof, of means for imparting a step-by-step rotary movement to said table, a piv- 15 oted centering-plate having a spring-activated bottle-engaging portion on one side of its pivot and a contact portion on the opposite side of its pivot, and a pivoted arm carrying a bottle-cradle movable toward and 20 from the periphery of said table and formed with a projection to engage said contact portion and thereby swing said bottle-engaging portion toward an advancing bottle in said cradle.

THOMAS F. LAMB.
